UNITED STATES PATENT OFFICE.

SHERWOOD HINDS, OF FORT WAYNE, INDIANA, ASSIGNOR TO S. F. BOWSER & COMPANY, INC., OF FORT WAYNE, INDIANA, A CORPORATION OF INDIANA.

DRIVING MECHANISM FOR COUNTERS.

1,425,964.

Specification of Letters Patent. Patented Aug. 15, 1922.

Original application filed September 26, 1917, Serial No. 193,257. Divided and this application filed May 17, 1920. Serial No. 381,869.

To all whom it may concern:

Be it known that I, SHERWOOD HINDS, a citizen of the United States, residing at Fort Wayne, in the county of Allen and State of Indiana, have invented certain new and useful Improvements in Driving Mechanism for Counters, of which the following is a specification.

This invention relates to mechanism for driving counters for use in connection with dispensing pumps and other devices, and has for its object the provision of mechanism of the class named which shall be of improved construction and operation.

The invention is exemplified in the combination and arrangement of parts shown in the accompanying drawings, and described in the following specification, and it is more particularly pointed out in the appended claims.

This application is a division of my prior application, Serial No. 193,257, filed September 26th, 1917, in so far as the mechanism of the present application is disclosed in the one referred to.

In the drawings—

Fig. 1 is a vertical sectional view through a portion of a dispensing pump showing one embodiment of the present invention;

Fig. 2 is a face view partly in section of the driving mechanism and adjustable take-up therefor shown in Fig. 1;

Fig. 3 is a vertical section substantially on line 3—3 of Fig. 2;

Fig. 4 is an elevation of the indicating dial for the mechanism shown in Figs. 1, 2 and 3;

Fig. 5 is a horizontal section through a dispensing pump showing a modified form of the invention applied thereto;

Fig. 6 is an elevation of the mechanism shown in Fig. 5 with parts in section;

Fig. 7 is a vertical sectional view substantially on line 7—7 of Fig. 5;

Fig. 8 is a sectional view; and

Fig. 9 is an elevation with parts in section of a modified form of expansion sprocket for use in connection with the mechanism shown in Figs. 5 and 6.

In my prior application, referred to above, I have disclosed and claimed a dispensing pump, such as is used for gasoline and other liquids, which has connected therewith an indicator and counter and an adjustable non-slip driving mechanism for

operating said indicator and counter from the drive shaft for the pump. As explained in that application, the cylinders for such pumps are not absolutely uniform in size and for this and other reasons, it is necessary to adjust the length of stroke of the various pumps in order to discharge a definite quantity of the liquid to be dispensed. This makes it necessary to adjust the driving connection between the pump mechanism and the indicator and counter in order that the movement of the indicator and counter may be kept uniform for different lengths of stroke of the pump. It is also desirable that there shall be no lost motion or slip between the driving mechanism and the counter in order that as soon as the pump begins to operate, the counter will begin to register the liquid which is being discharged. The operator of a pump, such as that shown by way of illustration in Fig. 1 and more completely described in my prior application referred to above, is usually on one side of the pump while the customer is on the other side, and consequently it is desirable to provide an indicating dial on each of the opposite sides of the pump. The customer's dial 10 is shown more clearly in Fig. 4, and the operator's dial 11, which comprises simply a pointer 12, is shown in Fig. 1. The customer's dial is also provided with a pointer 13 which is mounted on a common shaft 14 with the other pointer 12. Secured to the operating shaft 15 of the pump is a plate 16 formed with outwardly curved slots 17 in which pins 18 are slidable. These pins are secured to arcuate segments 19 and the segments may be moved radially outward from the axis of the shaft 15 by a relative movement of the plate 16 and the segments 19. To one of the segments a flexible band 20, preferably of metal, is secured by means of a fastening device 21. This band or ribbon 20 is wound upon and secured to a drum 22 which in turn is rotatably mounted upon a hub portion 23 of a fixed plate 24, the face of which plate constitutes the dial 10. Secured to the plate 24 and the drum 22 is a spring 25 which tends to keep the band 20 taut and to draw upwardly on it to take up the lost motion between the rack 26 of the pump and the driving pinion 27 therefor. In the plate 24, and extending around the graduations of the dial 10, is a circular slot 28 through

60

110

which projects a pointer 29 extending from the ribbon drum 22. At one end of the slot is the designation 0 and at other points around the slot are designations such as 5 $\frac{1}{2}$ gal., 1 gal. and 2 gal. designating the quantities pumped for a given position of the pointer 29, it being obvious that the pointer will assume these positions upon the actuation of the pump rack because of the 10 connection of the band 20.

Freely rotatable on the hub of the member 24, between it and the ribbon drum 22, is a Geneva stop gear 30 which has lugs 31 adapted to be engaged by a projection 32 of the ribbon drum 22. This gear also has 15 rearwardly extending toothed portions 33 which are spaced from the lugs 31. At the bottom of the plate 24, as shown in Figs. 2 and 3, is a Geneva pinion 34 with which 20 the gear 30 engages to rotate the pinion a predetermined amount upon each engagement of the toothed portion 33 with the pinion. As the particular pump illustrated 25 is a two gallon measure and as it may be set to pump either one or two gallons at each stroke, it is obvious that the Geneva pinion must be moved twice for a full stroke of the pump; in other words, if the ribbon drum 22 is simply rotated until the pointer 29 reaches the one gallon mark, the stop 32 will 30 engage only the uppermost lug 31, Fig. 4, which will move the lowermost toothed portion 33 to engage the pinion 34; but if the stop 32 is moved the entire length of the 35 slot 28 both toothed portions 33 will engage the pinion 34, causing it to be twice actuated. Of course, the reverse rotation of the Geneva stop gear 30 engages the pinion 34 and moves it backwardly the same amount 40 so that the gear 30 is simply oscillated back and forth one or two unit spaces by the engagement of the stop 32, depending upon the length of stroke of the pump. Meshing with the pinion 34 is a gear 35 which 45 carries a pawl 36 and this pawl engages a ratchet gear 37 fixed on the shaft 14. The rotation of the gear 35 in one direction causes the pawl 36 to actuate the ratchet gear 37 and cause a corresponding rotation of the pointers 12 and 13 which are attached to the shaft 50 14. Adjacent the ratchet gear 37 is a fixed member 38 which may be secured to the hub extension 23 of the plate 24, and mounted on this member 38 is a holding pawl 39 55 which engages the ratchet gear 37 and prevents its reverse rotation when the actuating pawl 36 is moved reversely and idly over the gear.

The ribbon drum 22 is preferably formed 60 with a hub extension 40 upon which is freely mounted a driving gear 41. Between this gear and the ribbon drum 22 is a spring-pressed roller clutch 42 which causes the rotation of the gear 41 when the ribbon 65 drum is rotated in one direction. Between

the fixed member 38 and the gear 41 is a roller clutch 43 which prevents the rotation of the gear 41 in the reverse direction. Meshing with the gear 41 is a spur and bevel pinion 44 which is directly connected 70 by a driving member 45 with a register 46 visible from the outside of the casing. As the driving gear 41 is actuated only in one direction of rotation and as the mechanism described is a single-action pump, it is obvious 75 that the register will accurately record the total amount discharged by the pump even though an insufficient quantity has been discharged to cause the units registers at the front and rear of the pump to indicate. The dials 10 and 11 are preferably 80 covered with glass and at the operator's end of the shaft is a knob 47 by means of which the pointers 12 and 13 can be freely rotated in one direction to set them at the zero 85 points. This is desirable for the reason that when a customer buys a quantity of the liquid dispensed, the pointers are set at zero marks and the operation of the pump, as above described, will cause the actuation of 90 the pointers to record the units of the quantity pumped whereupon the pointers can again be set upon the zero marks without in any way effecting the quantity register 46 which records the total amount pumped. 95

In varying the length of stroke of the pump rack to insure the accuracy of the pump, it is obvious that the graduation of the slot 28 would not remain the same for the different lengths of stroke; that is, if the 100 pump were set so that the pointer 29 would register exactly with the 2 gal. graduation on the slot 28 and then it were found that it would be necessary to increase the length of stroke of the pump in order to pump exactly two gallons, the pointer 29 would not stop at the 2 gal. mark when the pump stroke was increased unless some adjusting means were provided for taking care of the increased stroke. This is the object and 105 function of the adjustable circular segments 19 which are attached to the plate 16, for by moving them inwardly and outwardly, the length of the path of travel of the pointer 29 may be varied whenever the 110 length of stroke of the pump rack is varied so that the pointer will always register with the graduations of the slot, thereby insuring also that the total register 46 will accurately record the amount pumped. 115

Briefly stated it may be said that the segments 19 will be moved inwardly when the length of the pump stroke is increased and vice versa. The reciprocation of the rack 26 causes the actuation of the units 120 registering mechanism which records the number of units of measure (gallons) of the fluid pumped and also the actuation of the registering counter which thereupon measures the entire discharge of the pump 130

regardless of the number of units measure pumped. The various adjustments for the accuracy of the pump are, of course, made whenever necessary, it being observed, however, that with this style of pump it is unnecessary to have any access whatever to the interior of the casing of the pump in order to effect the ordinary operation thereof.

In the modified form of the invention shown in Figs. 5, 6 and 7, a pump casing 50 is illustrated having a shaft 51 journaled therein and arranged to be rotated by a hand crank 52 to operate a pinion 53. The pinion 53 meshes with and drives a pump rack 54 which operates a pump cylinder in a well known manner. Meshing with the pinion 53 is a second pinion 55 rotatably mounted on a stud shaft 56 and secured to a sleeve 57 which carries a sprocket wheel 58. A sprocket chain 59 engages the sprocket wheel 58 and passes around an expandible drum 60. Instead of providing an intermediate gear 55 and stud shaft 56, the sprocket wheel 58 may be mounted directly 20 on the pump shaft 51. This will eliminate any back lash or lost motion that may be present between the intermeshing gears 53 and 55. The side links 61 of the sprocket chain 59 are provided with comparatively 25 fine notches or serrations 62 which cooperate with similar serrations 63 on the adjustable segments 64 of the drum 60. The segments 64 are provided with tongues mounted to slide in grooves 65 formed in the face of a 30 plate 66. The face of the segments 64 opposite the plate 66 are provided with pins 67 which extend into inclined slots 68 formed in a cover plate 69. Screws 70 pass through elongated slots 71 in the plate 40 69 and are threaded into the plate 66. To adjust the diameter of the drum 60 the screws 70 are loosened and the plate 69 slightly rotated relative to the plate 66. This will force the pins 67 toward or away 45 from the center of the drum, depending upon the direction of relative rotation of the plates 68 and 69. When the drum is adjusted to the proper diameter the screws 70 are again tightened and clamp the plate 50 69 and segments 64 in fixed position relative to the plate 66. The plate 66 is provided with a projecting hub portion 72 which extends into a circular recess in a rotary member 73. Ratchet rollers 74 are 55 provided between the members 72 and 73 to constitute a one-way drive between the plate 66 and the rotary member 73. The rotary member 73 is seated in a recess formed by a fixed flange 75 on the pump 60 casing 50 and ratchet rollers 76 constitute a one-way holding ratchet between the members 73 and 75. When the drum 60 is driven by the sprocket chain 59, during the pumping stroke of the rack 54, the projection 72 on the plate 66 will operate the

rotary member 73 through the ratchet drive 74. On the reverse stroke of the rack 54 the member 73 will be held against rotation by the ratchet rollers 76 and the projection 72 will rotate freely in a reverse direction 70 in the recess in the member 73. The member 73 is provided with a sleeve 77 rotatably mounted on a stud shaft 78 and connected at its end with a pinion 79 so that the pinion 79 is rotated whenever the member 73 is driven by the drum 60. The pinion 79 is connected by suitable gearing 80 to any well known form of counter. By this arrangement the counter will be driven during the pumping stroke of the rack 54 80 but will remain stationary during the idle stroke of the rack. A chain-tightener comprising a roller 81 carried by an arm 82 pivotally mounted on a pin 83 is provided for maintaining constant tension in the 85 driving run of the chain 59. The tension on the chain 59 is produced by a spring 84 which bears upon the arm 82 on the side of the pin 83, opposite the roller 81.

In the form of expandible drum shown 90 in Figs. 8 and 9, a plurality of segments 85 are provided with tongues 86 arranged to slide in grooves 87 in a plate 88. The plate 88 is provided with a projecting hub 89 threaded to receive a cone 90 which extends into a central opening in a cover plate 91 and bears against the inner faces of the segments 85. A spring 92 is housed in a recess 93 in the segments 85 and normally draws the segments 85 against the beveled 100 face of the cone 90. Screws 94 pass through openings in the plate 91 and are threaded into the plate 89. To adjust the diameter of the drum, the screws 94 are loosened and the cone 90 is rotated on the threaded hub 89 105 to cause it to move in or out and thus shift the segments 85 to adjust the diameter of the drum. When the desired diameter has been secured, the screws 94 are again 110 tightened to hold the segments in their adjusted positions. The construction of this form of drum may be in other respects similar to that shown in Figs. 5, 6 and 7. It will be understood that the drum shown in Fig. 2 may be provided with expansion 115 mechanism similar to that shown in either Fig. 7 or Figs. 8 and 9, and that the form of flexible driving element shown in Figs. 8 and 9 may be substituted for the strap shown in Fig. 1. With the continuous driving chain shown in Figs. 8 and 9, the amount of movement in one direction is not limited as it is in the case of a strap secured to the rotary elements in the manner shown in Fig. 1.

I claim:

1. Driving mechanism for a registering device comprising a rotary member, means for adjusting the peripheral length of said member, flexible means engaging the pe- 130

- iphery of said member for transmitting motion therefrom to said registering device, and means for maintaining said flexible means taut at all times.
- 5 2. Driving means for a registering device comprising a pair of rotary sheaves, a flexible band for transmitting motion from one of said sheaves to the other, means for preventing said band from slipping relative to 10 said rotary sheaves, means for adjusting the peripheral length of one of said rotary sheaves, and means for maintaining said flexible band taut at all times.
- 15 3. Driving mechanism for connecting a reciprocating member with a registering device, said mechanism comprising a pair of rotary members, a flexible element engaging the peripheries of said members for transmitting motion from one to the other 20 thereof, means for preventing said element from slipping on said rotary members, means for adjusting the diameter of one of said rotary members, and ratchet mechanism connected with one of said rotary 25 members for transmitting motion to said registering device in one direction only.
4. Mechanism for transmitting motion from a reciprocating member to a registering device therefor comprising a pair of 30 rotary sheaves, a flexible element engaging the peripheries of said sheaves for transmitting motion from one to the other thereof, means for preventing said flexible element from slipping on the surface of said 35 rotary sheaves, yielding means for maintaining tension in said flexible element to prevent lost motion between said reciprocating member and said registering device, means for expanding the diameter of one 40 of said rotary sheaves to increase the peripheral length thereof and regulate the amount of movement of said registering device for different movements of said reciprocating member, ratchet mechanism connected with one of said rotary members for 45 transmitting motion to said registering device when said reciprocating member is moved in one direction and for preventing return movement when said reciprocating 50 member is moved in the opposite direction.
5. Mechanism for transmitting movement from a reciprocating member to a registering device therefor comprising a pair of rotary members, a flexible element engaging the peripheries of said members for transmitting motion from one to the other thereof, one of said members having a plurality of segments arranged to move radially to adjust the peripheral length thereof for regulating the 55 amount of motion transmitted to said registering device for different movements of said reciprocating member, means for locking said segments in adjusted positions,
- means for preventing said flexible element 65 from slipping relative to said rotary members, and means for maintaining said flexible element taut at all times.
6. Registering mechanism for a measuring pump having a reciprocable member 70 and means for adjusting the length of stroke for accuracy; said registering mechanism comprising a graduated dial, indicating means movable relative to said dial amounts proportional to the movement of 75 said reciprocating member for showing the full quantity pumped at each stroke, a connection between the indicating means and the reciprocable member of said pump for varying the actual relative movement of 80 said members while maintaining the proportionality thereof to permit a variation of the length of stroke of the reciprocable member while maintaining constant the length of stroke of the indicating means 85 and mechanism actuated by said connection for registering the total of a plurality of indicated amounts.
7. Registering mechanism for a measuring pump having a reciprocable member, 90 means for varying the length of stroke thereof to form different units of quantity, and separate means for adjusting the length of stroke of the reciprocable member for accuracy of discharge; said registering 95 mechanism including indicating means comprising a graduated slot, a visible pointer movable therein to show the quantity actually pumped at each stroke, and an adjustable connection between the 100 pointer and the reciprocable member of said pump for indicating the length of stroke and also variable to register with the graduations of the slot independent of the adjustability for accuracy of the reciprocable 105 member.
8. Registering mechanism for a measuring pump having a reciprocable member and means for adjusting the length of stroke thereof for unit variation of quantity and 110 for accuracy of measurement; said mechanism comprising a register for visibly indicating the amount pumped at each stroke and depending for its accuracy of measurement upon a constant length of stroke, and 115 an adjustable connection between the register and the reciprocable member for maintaining a constant length of stroke for the register regardless of the variation in length of stroke of the reciprocable member. 120
9. Registering mechanism for a measuring pump having a reciprocable member adjustable in its length of stroke for accuracy of pumping, said mechanism comprising a register for visibly indicating the amount 125 pumped at each stroke and depending for its accuracy upon a constant length of stroke for a given quantity, stroke-indicating means

- connectable with the register and comprising a graduated slot and a pointer movable therein, and an adjustable connection between the pointer and the reciprocable member of said pump for maintaining the length of stroke of the pointer constant for any given quantity regardless of the adjustment of the reciprocable member. 5
10. Registering mechanism for a single-acting measuring pump having a reciprocable member and means for adjusting the length of stroke thereof for accuracy of the pump; said mechanism comprising a recording meter therefor depending for its accuracy upon a constant length of stroke and operated by the movement of the reciprocable member in one direction only, stroke-indicating means (having a visible moving pointer,) and a separately adjustable connection with the reciprocable member, and a one-way clutch between said mechanism and the meter for recording the total quantity pumped. 15
11. Registering mechanism for a single-acting self-measuring pump having a reciprocable member with an adjustable length of stroke for accuracy in pumping, said mechanism comprising indicating means (having a graduated slot and a visible pointer movable therein), and an adjustable means for varying the length of stroke of the pointer comprising a flexible band, and rotatable means with radially adjustable segments upon which the band is wound. 20
12. Registering mechanism for a measuring pump having a reciprocable member of which the length of stroke is adjustable for accuracy in pumping and rotatable means for actuating the reciprocable member; said mechanism comprising a circular stroke-indicating means having a graduated slot, a visible pointer movable therein, a separately adjustable driving connection for the pointer comprising a flexible band, and a rotatable device in connection with the said rotatable means, said device having radially adjustable segments upon which the band is wound. 25
13. Registering mechanism for a measuring pump having a reciprocable member of which the length of stroke is adjustable for accuracy in pumping and rotatable means for actuating the reciprocable member; said registering mechanism comprising stroke-indicating means having a circular graduated slot and a visible pointer movable therein, and an adjustable connection between the pointer and the driving means for said reciprocable member, said adjustable connection comprising a rotatable member for carrying the pointer, a band attached thereto, and a rotatable device attached to the said rotatable actuating means to which the band is also attached, the said device comprising radially adjustable seg- 30
- ments upon which the band is wound for varying the length of stroke of the pointer by the variation of the said segments. 35
14. Registering mechanism for a measuring pump having a reciprocable member and a rotatable driving means for the member, said mechanism comprising a stroke-length indicating means for the pump having a visible rotatable pointer, a rotatable member to which the pointer is attached, a flexible connection between the said member and the rotatable driving means, and a spring acting upon the member tending to hold taut the flexible connection. 40
15. Registering mechanism for a measuring pump having a reciprocable member and rotatable driving means, said mechanism comprising a stroke length indicating mechanism including a pointer, recording mechanism therefor comprising a rotatable member, a Geneva gear operated by the member, a pinion operated by the gear, an intermittent register operated by the pinion, and a connection between the rotatable driving means and the said rotatable member of the indicating and recording mechanism. 45
16. An indicating and recording mechanism for measuring pumps comprising a rotatable member having a projection and carrying a visible stroke-indicating pointer, a graduated dial over which the pointer moves, a Geneva gear having lugs engageable by the projection and oscillatable with the member, a Geneva pinion intermittently operated by the gear, a ratchet gear intermittently actuated by the pinion, and a rotatable pointer connected for operation to the said ratchet gear. 50
17. A registering device for a measuring pump having a rotatable driving member, said device comprising a single mechanism for visibly indicating the length of stroke of the pump for intermittently recording the number of units-measures pumped, and for permanently recording the total quantity pumped independent of the units register, and an adjustable connection between the pump and the said mechanism. 55
18. A non-slip driving mechanism for an indicator comprising two rotary members, one of said members having radially movable segments for adjusting the diameter of said member, the outer faces of said segments being serrated, a flexible element engaging the peripheries of said rotary members and having serrations thereon to engage the serrations on the faces of said segments, means on the other of said rotary members to prevent slipping of said flexible element thereon, and yielding means to maintain said flexible element taut on said rotary members. 60
19. A registering device for pumps comprising a drum arranged to rotate during the movement of the pump, a flexible band 65

6
engaging the periphery of said drum for transmitting movement from the pump to a registering device, and means for expanding said drum to increase the peripheral length 5 thereof to vary the speed ratio between said drum and the registering device.

20. The combination with a pump, of a registering device therefor, of means for transmitting movement from said pump to 10 said registering device, said movement transmitting means comprising a drum having a plurality of segmental members connected therewith, means for shifting said segments radially of said drum to increase 15 the peripheral length of said drum, and a flexible member for transmitting movement between said drum and registering device.

21. The combination with a pump and register therefor, of means for transmitting motion from said pump to said register, said 20 transmitting means comprising a drum having a plurality of segmental members connected therewith, means for simultaneously shifting said segmental members equal amounts radially to increase the peripheral 25 length of said drum, and a flexible member for engaging the periphery of said drum and transmitting motion between said drum and registering device.

In testimony whereof I have signed my 30 name to this specification on this 26th day of April, A. D. 1920.

SHERWOOD HINDS.
